CONDENSER TUBE PROTECTOR

Thomas J. Bay, United States Navy

Application May 9, 1938, Serial No. 206,827

3 Claims. (Cl. 285—54)

(Granted under the act of March 3, 1883, as
amended April 30, 1928; 370 O. G. 757)

This invention relates to condenser tubes and it has a particular relation to inserts for preventing the corrosion of the tubes adjacent to their inlet ends by the water passing therethrough.

5 Modern condenser design makes use of high water velocities in the condenser tubes in order to secure improved heat transfer rates of the cooling surface and thereby reduce the size of the unit required for a given heat load. These high water 10 velocities cause the early failure of the inlet ends of the condenser tubes due to impingement erosion and electro-chemical corrosion of the tube material. This action is especially severe in condensers employing tubes which are rolled and expanded into the condenser header plates, as the cold working of the tube material at the inlet end of the tube serves to weaken it structurally and produce fatigue so that its resistance to the destructive forces imposed by the high velocity of 20 the water entering the tube is reduced.

The principal object of the present invention is the provision of an insert for the inlet end of a condenser tube, said insert being constructed of a material which is chemically inert with respect 25 to the metal of the tube and condenser header plate, such as rubber or synthetic rubber which possesses high resistance to abrasion in the form of impingement erosion and which seals the junction of the tube and header plate against the electro-chemical action of the water or other electrolyte passing therethrough.

With these and other objects in view, as well as other advantages that may be incident to the use of the improvements, the invention consists in 30 the parts and combinations thereof hereinafter set forth and claimed with the understanding that the several necessary elements constituting the same may be varied in proportion and arrangement without departing from the nature and 35 scope of the invention, as defined in the appended claims.

In order to make the invention more clearly understood, there are shown in the accompanying drawing, means for carrying the invention into 40 practical use, without limiting the improvements in their useful application to the particular construction, which, for the purpose of explanation, have been made the subject of illustration.

In the accompanying drawing: 45

50 Fig. 1 is a longitudinal sectional view through a portion of a condenser tube and condenser header plate showing the improved insert secured in position;

55 Fig. 2 is a side elevational view of the condenser tube insert;

Fig. 3 is an end view of the insert shown in Fig. 2 as viewed from the right;

Fig. 4 is a longitudinal sectional view taken on line 4—4 of Fig. 3; and

Fig. 5 is a view similar to Fig. 1 but showing another form of tube insert embodying the invention.

Referring to the drawing and particularly to Figs. 1 to 4 thereof, a condenser tube 10 is shown as being secured in a condenser header plate 11 10 the outer or inlet end of the tube being flared as indicated at 12. An insert 13 constructed of a material which is chemically inert with respect to the metal of the tube and header plate, such as rubber or synthetic rubber, is secured within 15 the inlet end of the tube 10 by cement or by vulcanizing. The outer end of the insert 13 is flared and curved inwardly as at 14 so as to enclose the outer flared end 12 of the tube so as to effectively seal the juncture of the tube and plate 20 against any electro-chemical action of the water or other electrolyte passing through the tube. The insert 13 is contoured so as to provide a restricted throat 15 which gradually increases in 25 diameter inwardly until it merges with the diameter of the tube 10. The contour of the throat 15 corresponds substantially to the contraction and enlargement of a stream of water passing through an orifice, thereby minimizing turbulence and the 30 liberation of air from the water and also eliminates impingement erosion and friction loss in the jet of water entering the tube.

In Fig. 5 there is shown a slightly modified form of condenser tube and insert. In this construction the tube 10 terminates short of the outer 35 surface of the heater plate 11, the latter being countersunk, as at 16 to receive a flared enlargement 17 of the insert. This provides a flush outer surface and an effective seal between the water and the metals of the tube and plate.

The rubber from which the insert is fabricated possesses high resistance to abrasion in the form of impingement-erosion, chemical inertness with respect to the metal used in condenser construction, is waterproof and has high electrical insulating properties.

The protective tube insert herein described provides a simple and effective means for protecting the inlet ends of condenser tubes from the destructive forces mentioned and greatly prolongs 50 their service life.

It will be understood that the above description and accompanying drawing comprehend only the general and preferred embodiment of the invention, and that various changes in the construction, 55

proportion and arrangement of the parts may be made by those skilled in the art, without departing from the nature and scope of the invention as defined in the appended claims.

5 5 The invention described herein may be manufactured and/or used by or for the Government of the United States of America for governmental purposes without the payment of any royalties thereon or therefor.

10 10 I claim:

1. Means for protecting from corrosion the end of a tube extending through a header plate comprising a tubular insert of resilient material secured in the inlet end of said tube and sufficiently 15 expandable to closely conform to irregularities in the configuration thereof for absorbing the impact of media entering said tube.

2. Means for protecting from erosion the end of a tube extending through a header plate com-

prising a tubular insert of rubber-like material secured in the inlet end of said tube and sufficiently expandable to closely conform to irregularities in the configuration thereof for absorbing the impact of media entering said tube.

3. Means for protecting from corrosion the end of a tube extending through a header plate comprising a tubular insert of resilient material secured in the inlet end of said tube and sufficiently expandable to closely conform to irregularities in 10 the configuration thereof for absorbing the impact of an electrolyte entering said tube, said insert having an annular flange at its outer end embracing the juncture of said tube and plate to exclude said electrolyte therefrom and composed of 15 a material which is chemically and physically inert with respect to said tube, plate and media at the normal temperature thereof.

THOMAS J. BAY.
